UNITED STATES PATENT OFFICE.

CHARLES F. SMITH, OF NEW BRITAIN, CONNECTICUT, ASSIGNOR TO THE
LANDERS, FRARY & CLARK, OF SAME PLACE.

RIGHT AND LEFT HAND STOP AND WASTE COCK.

SPECIFICATION forming part of Letters Patent No. 633,916, dated September 26, 1899.

Application filed June 16, 1899. Serial No. 720,868. (No model.)

To all whom it may concern:

Be it known that I, CHARLES F. SMITH, a citizen of the United States, residing in New Britain, in the county of Hartford and State of Connecticut, have invented certain new and useful Improvements in Right and Left Hand Stop and Waste Cocks, of which the following is a specification.

My invention relates to improvements in right and left hand stop and waste cocks; and the objects of my improvement are simplicity of construction and convenience in operation.

In the accompanying drawings, Figure 1 is a rear elevation of my stop-cock. Fig. 2 is a sectional plan of the same, the plug and handle-stem being shown in horizontal section on the line *xx* of Fig. 1. Fig. 3 is a sectional view, partly in elevation, the plane of section being indicated by the line *yy*, Fig. 2. Fig. 4 is a side elevation of a T-handle that may be used interchangeably with the lever-handle shown in Figs. 1 and 3. Fig. 5 is a front elevation of my stop-cock in a modified form. Fig. 6 is a sectional plan of the same, the plug and handle being shown in horizontal section on the line *zz*, Fig. 5. Fig. 7 is a horizontal section on the line *ss* of Fig. 5, the handle being removed. Fig. 8 is a sectional view, partly in elevation, the plane of section being indicated by the line *tt*, Figs. 6 and 7.

The body A, pipe connections 5 and 6, and main portion of the tapering plug B, together with their various water-passages, are of an ordinary construction, the plug being held in place by the usual nut 7.

On the body A are two stop-shoulders 8, and on the plug is a fixed pin 9 and a removable stop 10, the latter being screw-threaded, while the plug is provided with two threaded stop-sockets 11 on diametrically opposite sides, into either one of which the removable stop may be secured. The end of the plug is provided with a handle-socket 12, preferably of an angular form in cross-section, either with or without the side recesses 13, and the handle C is provided with a stem 14, fitted to the said socket 12 and, if desired, provided with side webs or ribs 17 to fit the recesses 13, whereby the handle-stem can be inserted in the socket in only two different positions, representing a half-revolution of the handle

on the plug, in both of which the handle is parallel to the main passage 15 through the plug. The removable stop 10 in addition to its stop function may serve as a set-screw 55 for securing the handle-stem in the plug. Two side faces of the fixed pin form fixed stops for engaging the stop-shoulders 8 on the body of the cock. The main passage and waste-passage in the plug are indicated by 60 broken lines in Fig. 2, the said waste-passage when the handle and plug are in the position shown being on that side which is opposite the said waste-nozzle 16, Fig. 2.

In Figs. 1, 2, and 3 the removable stop 10 65 is in contact with one of the stop-shoulders 8 on the body A, while the fixed pin is midway between said shoulders. The handle is parallel to the pipe connections 5 and 6, and the main passage in the plug is opened, while the 70 waste-nozzle is closed. By turning the handle and plug a quarter-turn one side of the fixed pin will be in contact with one of the shoulders 8 on the body A and the removable stop will be midway between said shoulders, 75 while the main passage through the plug will be closed and the waste-nozzle opened to drain the pipe that is secured to the pipe connection 5, that being (with the adjustment shown) the house side. In order to change the cock 80 for the other hand, it is only necessary to unscrew and remove the removable stop, take out the handle, change its position on the plug one-half of a revolution, and then replace it and secure the removable stop in the dia- 85 metrically opposite socket from that in which it was before secured.

The modification shown in Figs. 5 to 8 is the same as the construction hereinbefore described excepting that I substitute for the 90 fixed pin with two faces for acting on the stops 8 a fixed lug 9^a with two faces in the body A for acting on two stops of the plug B^a, which stops 8^a are formed at the ends of the peripheral groove 18 in the said plug and 95 into which groove the end of the lug 9^a projects. The relation of the lug 9^a to the groove 18 and its ends or stops is such that when the handle and plug are set with the main passage 15 in line with the pipe connections the 100 plug may be turned a quarter-revolution in either direction unless said movement is ob-

structed by the removable stop. The operation is precisely the same as before, only the plug is stopped with the removable stop midway between the stop-shoulders 8 8 by means of the fixed lug 9^a of the body and fixed stops 8^a of the plug instead of by the sides of the fixed pin of the plug and lugs 8 8 of the body. The two sides of the fixed pin 9 in the first construction and the two ends of the groove 18 in the second construction constitute fixed stops of the plug, and they both act to stop the plug in precisely the same relation to the removable stop 10.

I have shown a lever-handle C in Figs. 1 and 3; but, if desired, the T-handle C², Fig. 4, may be inserted in the same socket in the same way, the shank 14 being also formed to fit the said socket. In like manner any desired form of handle or operating device may be fitted 20 to the plug for use therewith—as, for example, a hydrant-rod handle—by merely providing the same with a stem 14 and, if desired, with a web or rib 17 to fit the socket 12 in the plug. I am aware that cocks have heretofore been 25 described in several patents as having a plug provided with a socket and with handles provided with a stem fitted to said socket and

held in place by a screw bearing on the said stem, and the same is hereby disclaimed.

I claim as my invention—

1. In a right and left hand stop and waste cock the combination of the body provided with two stop-shoulders, the plug fitted to said body, and provided with fixed stops, a removable stop and diametrically opposite sockets in the plug for alternately receiving the said removable stop, and a handle, substantially as described.

2. In a right and left hand stop and waste cock, the combination of the body provided with the two stop-shoulders, the plug fitted thereto, having a handle-socket and provided with fixed stops and with diametrically opposite sockets for receiving a stop, a removable stop adapted to be secured in either of the said stop-sockets of the said plug, and a handle having a stem fitted to the handle-socket of the plug and adapted to be fastened in place by the said removable stop, substantially as described.

CHARLES F. SMITH.
